CLAIM

(57) The ornamental design for LED light module, as shown and described.

DESCRIPTION

FIG. 1 is a perspective view of an LED light module showing a first embodiment of our new design;
FIG. 2 is a top plan view thereof;
FIG. 3 is a bottom plan view thereof;
FIG. 4 is a side elevational view from a front side thereof;
FIG. 5 is a side elevational view from a rear side thereof;
FIG. 6 is a side elevational view from a left side thereof; and,
FIG. 7 is a side elevational view from a right side thereof.
The broken lines in the figures represent unclaimed subject matter and form no part of the claimed design.
